US00D794013S

(12) **United States Design Patent** (10) Patent No.: **US D794,013 S**
(45) Date of Patent: ** Aug. 8, 2017

(54) **BODY-WORN PORTABLE ELECTRONIC DEVICE**

(71) Applicant: **Samsung Electronics Co., Ltd.**, Suwon-si, Gyeonggi-do (KR)

(72) Inventors: **Felix Heck**, London (GB); **Ju-Suek Lee**, London (GB); **Yu-Na Oh**, London (GB); **Hyun-Taik Lim**, London (GB); **Aleix Ingles**, London (GB); **Craig Morrison**, London (GB); **Maxence Couthier**, London (GB); **Ji-Eun Lee**, Seoul (KR)

(73) Assignee: **SAMSUNG ELECTRONICS CO., LTD.**, Suwon-si, Gyeonggi-Do (KR)

(**) Term: **14 Years**

(21) Appl. No.: **29/521,076**

(22) Filed: **Mar. 19, 2015**

(30) **Foreign Application Priority Data**

Sep. 19, 2014 (KR) 30-2014-0045550

(51) LOC (10) Cl. **14-02**

(52) U.S. Cl. **USPC D14/344; D24/186; D11/5**

CLAIM

The ornamental design for a body-worn portable electronic device, as shown and described.

DESCRIPTION

FIG. 1 is a front perspective view of a body-worn portable electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof; and,

FIG. 7 is a bottom plan view thereof.

The broken lines are shown in the drawings illustrate portions of the body-worn portable electronic device that form no part of the claimed design.

1 Claim, 7 Drawing Sheets
